(57) **CLAIM**

The ornamental design for a slide attachment, as shown and described.

DESCRIPTION

FIG. 1 is a front and side perspective view of a slide attachment having our new design;

FIG. 2 is a top plan view thereof;

FIG. 3 is a bottom plan view thereof;

FIG. 4 is a right elevational side view thereof;

FIG. 5 is a left elevational side view thereof;

FIG. 6 is a back elevational view thereof; and,

FIG. 7 is a front elevational view thereof.

The broken lines in the figures are for illustrative purposes only and form no part of the claimed design.
